UNITED STATES PATENT OFFICE.

ALBERT T. VAN ALSTYN, OF NEW YORK, N. Y.

BUCKLE.

1,136,451.

Specification of Letters Patent. Patented Apr. 20, 1915.

Application filed August 28, 1911. Serial No. 646,346.

To all whom it may concern:

Be it known that I, ALBERT T. VAN ALSTYN, a citizen of the United States, residing at New York, in the county of New York and State of New York, have invented certain new and useful Improvements in Buckles, of which the following is a specification.

This invention relates to improvements in buckles, and one of the objects of the invention is to provide an improved, simple, durable and cheap buckle particularly adapted to effectively hold various thicknesses of fabric or other material.

15 A further object is to provide an improved buckle of this class which will automatically adjust itself to the thicknesses of the material to be held.

To the attainment of these ends and the accomplishment of other new and useful objects, as will appear, the invention consists in the features of novelty in substantially the construction, combination and arrangement of the several parts hereinafter more 25 fully described and claimed and shown in the accompanying drawing exemplifying the invention, and in which—

Figure 1 is a perspective view of a bandage and support, having an improved buckle applied thereto constructed in accordance with the principles of this invention. Fig. 2 is a front elevation of the buckle. Fig. 3 is a side elevation of Fig. 2. Fig. 4 is a longitudinal sectional view, showing the position the parts will assume when fabric of some thickness is placed in the buckle. Figs. 5, 6 and 7 are detached detail views of portions of the buckle. Fig. 8 is a sectional view on line 8—8, Fig. 2. Fig. 9 is a view 40 taken on line 9—9, Fig. 2, looking in the direction of the arrows. Fig. 10 is a detail sectional view of a modified form.

Referring more particularly to the drawing and in the present exemplification of this invention, the numeral 10 designates generally the body of the buckle, which may be constructed of any size and configuration and of any suitable sheet material such as metal or the like, and is provided with 50 flanges 11 projecting laterally beyond one face thereof adjacent the side edges of the body and extending the entire length thereof. The lower extremities 12 of the flanges 11 are coiled or bent inwardly, as shown, to 55 form guides for a purpose to be hereinafter set forth. A portion of the body 10 is cut

away as at 13 to form an aperture therethrough, and a portion of the cut-out portion is removed while the remaining portion is bent upwardly as at 14, to form an upwardly opening hook or bearing which terminates short of the flanges 11 and is preferably located below the upper edge 15 of the body. The body 10 is also cut out and the cut out portions are deflected between the flanges 11 to form laterally-projecting teeth 16.

A guide frame, constructed of any suitable flexible material such as wire or the like, is formed with spaced parallel arms 17, and a laterally off-set portion 18 at one extremity of the arms. The free end of each arm 17 is also deflected laterally as at 19, and the extremity of these off-set portions 19 are bent downwardly as at 20. These portions 20 may be of any desired length and are adapted to move in the guides 12. The deflected portion 18 of the guide member is adapted to engage over or rest within the open hook 14, and when placed in position the extremity of this hook may be deflected so as to secure the guide against accidental displacement. The extremities 20 of the guide member are adapted to enter and move within the respective guides 12, 75 and are of such a length that the arms 17 of the guide member may be deflected to some extent without causing the accidental disengagement of the extremities 20 from the guides 12.

Movably mounted upon the guide is a support which is constructed of any suitable material such as wire or the like, and comprises a body portion 21, the extremities of which are deflected and coiled as at 22 to 80 form spaced tubular portions. These tubular portions receive the respective arms 17 of the guide and the slide may be mounted upon the guide before the extremities of the arms are deflected. When thus mounted, 100 the slide is free to move on the arms. A tongue member designated generally by the reference numeral 23 is pivotally mounted upon the slide 21 between the tubular portions 22 so as to stand between the arms 17. 105 This tongue member is provided with a laterally deflected portion 24 at one extremity and the free edge of which portion may be smooth or corrugated as desired. This free edge is adapted to coöperate with 110 the teeth 16 in the body portion 10.

The buckle may be employed for any pur-

pose, but in the present exemplification of the invention it is shown in connection with a bandage or napkin 26, the extremity of which napkin is adapted to be projected 5 through the opening 13 in the body portion 10 of the buckle from the rear and then pulled down over the face of the body portion 10, the same being held in place by one hand while with the free hand the slide 21 is forced down over the napkin to the lower 10 extremity of the arm 17. In this position the tongue member 23 is pivotally turned to engage the napkin, thus securely fastening or locking the napkin in the buckle, as 15 the free edge of the deflected portion 24 of the tongue member 23 will be disposed below the teeth 16 on the body portion 10. In this position the elasticity of the arms 17 will force the laterally deflected portion of 20 the tongue member against the napkin and will in turn force a portion of the napkin beneath the teeth 16, as shown in Fig. 4, in which position the extremity of the napkin will be securely held to the buckle. It will 25 be manifest that the elasticity of the arms 17 will permit the tongue member 23 to be automatically adjusted so that the buckle will accommodate itself to varying thicknesses of fabric. When the fabric is secured 30 within the buckle, the free extremity of the tongue member will stand in close proximity to the extremity 27 of the napkin. When it is desired to remove the napkin, all 35 that is necessary is to grasp the free end 27 thereof and raise it upwardly or away from the base 10. This movement will cause pressure on the free end of the tongue member to rock the tongue about its point of pivotal support with the slide 21 and thereby move 40 the free edge of the laterally deflected portion 24 of the tongue member away from the fabric to release the latter. A further movement of the free extremity of the napkin in the same direction will cause the slide 21 together with the tongue 23 to move upwardly 45 toward the top of the arms 17, in which position it may be retained by grasping the slide with one hand, so as to permit the napkin to be freely removed or the extremity 50 thereof to be readily inserted in the buckle. When the slide is released, it will gravitate toward the bottom of the arms, and when the tongue member is turned about its pivotal support on the slide, the laterally deflected portion 24 will coöperate with the teeth 16 to secure the napkin.

The buckle thus constructed may be secured to the body band 28 in any suitable manner, such as by means of a tab 29 one 60 extremity of which is secured to the body band and the other extremity passes through a loop 30, which loop is connected with the buckle in any suitable manner such as by means of an elastic member 31, which 65 engages over the top edge 15 of the body of

the buckle by passing through the opening 13 therein. The free extremity of the tab 29 is bent back upon the tab and is secured by any suitable fastening device 32.

It will thus be manifest that with this improved construction the fabric will not only be securely held by the buckle, but the elasticity of the arms 17 of the guide will permit the buckle to automatically accommodate itself to varying thicknesses of fabric. 70 When the arms 17 are deflected as shown in Fig. 4, the extremities 20 thereof will slide freely in the guides 12. If the fabric is comparatively thin, it will be effectively held by the buckle owing to the fact that the 75 arms 17 of the guide when the latter are substantially parallel with the body 10, will hold the deflected portion 24 of the buckle against the fabric with sufficient tension to coöperate with the teeth 16 of the body 10 and thereby hold the fabric against slipping. Furthermore, the napkin may be removed and the buckle detached from the body band, so that the band and napkin may 80 be washed, after which the buckle may be 85 again readily attached to the band. 90

In Fig. 10 the guides 12^a on the body portion are preferably spaced a short distance from the extremities of the body. The ends of the arms 17^a are bent to form coils 17^b with the extremities 17^c forming return bends. These return bends are inserted in the guides 12^a from the lower edge of the body portion 10 when the latter is held uprightly so that the extremities will move 100 freely in the guides 12^a. The coils 17^b are located beyond the extremity of the body portion, and the axes of these coils are substantially parallel with the pivot of the elastic members or guides 17^a. 105

What is claimed as new is—

1. In a buckle, the combination of a buckle frame, flexible guides supported thereby, a cross bar mounted to slide upon the guides, and a clamping member pivotally mounted 110 upon the cross bar.

2. In a buckle, the combination of a buckle frame, an elastic support mounted upon the frame, a slide movable on the support, and a clamping member mounted upon the slide 115 to coöperate with the buckle frame.

3. In a buckle, the combination of a buckle frame, an elastic guide, one end of said guide being fixed to the frame, the other end having a yielding connection with the 120 frame, and a clamping member slidably connected with the guide and pivotally supported with respect to the guide.

4. In a buckle, the combination of a buckle frame, an elastic guide supported by the 125 frame, a portion of the guide being fixed with respect to the frame, another portion of the guide having a sliding connection with the frame, a clamping member slidably mounted upon the guide and supported 130

- for pivotal movement with respect to the guide.
5. In a buckle, the combination of a frame, spaced elastic guides pivotally connected adjacent one end with the frame, the other ends of the guides having sliding connection with the frame, a slide movable on the guides, and a clamping member supported by the slide for pivotal movement with respect to the slide and guides.
10. 6. In a buckle, the combination of a frame, guides supported by the frame and laterally yieldable with respect to the frame, a clamping member mounted to slide upon the guides, and means supporting the clamping member for said sliding movement and for pivotal movement with respect to the guides on an axis disposed transversely with respect to the guides.
20. 7. In a buckle, the combination of a frame, spaced elastic guides, means pivotally connecting the guides at one end to the frame, open guides on the frame spaced from the point of pivotal connection of the elastic guides with the frame, the free extremities of the elastic guides being shaped to slide freely in the respective open guides, a slide mounted upon the elastic guides, and a clamping member pivotally supported by the slide.
30. 8. In a buckle, the combination of a frame, spaced elastic guides pivotally connected adjacent one end with the frame, the other ends of the guides being shaped to form return bends, guides on the frame to receive the return bends, and in which the latter freely move, a slide movable on the elastic guides, and a clamping member supported by the slide for pivotal movement with respect to the slide and guides and on an axis disposed transversely with respect to the guides.
40. 9. In a buckle, the combination of a frame,

spaced elastic guides pivotally connected adjacent one end of the frame, the other ends of each of the guides being shaped to form coils with the extremities forming return bends, said coils being disposed beyond the edge of the frame and with their axes substantially parallel with the axis of the pivot of the elastic member, and a clamping member supported by the guides for sliding and for pivotal movements with respect thereto.

10. In a buckle, the combination with a buckle frame, of a flexible guide mounted on the frame, and a clamping member elastically supported by the guide and mounted both for free sliding movement thereon and for pivotal clamping movement with the frame.

11. In a buckle, the combination with a buckle frame, of flexible guides at the sides of the frame, and a clamping member elastically mounted on the guides for free sliding movement thereon and pivotally mounted between the guides for clamping movement with respect to the frame.

12. In a buckle, the combination with a buckle frame having an intermediate toothed projection, of flexible guides at the sides of the frame and a clamping member elastically mounted on the guides for free sliding movement thereon having a clamping portion between the guides and pivotally mounted for movement between the guides for a clamping action with respect to the teeth of the frame.

In testimony whereof I have signed my name to this specification, in the presence of two subscribing witnesses, on this 8th day of June A. D. 1911.
